CORE CATCHER

John S. Goodwin, Whittier, Calif., assignor to
 Globe Oil Tools Company, Los Nietos, Calif., a
 corporation of California

Application April 10, 1945, Serial No. 587,453

6 Claims. (Cl. 255—72)

1

This invention relates to core catchers and relates more particularly to core catching and mounting means for embodiment in a well tool. An object of my invention is to provide a simple, practical and effective core catcher for a well drill or a well core drill which is positive and dependable in operation.

Another object of my invention is to provide a well tool in which a core catcher, embodied in a core drill, has a maximum feasible core opening whereby the capacity of the tool is as great as possible.

Another object of my invention is to provide a well drilling tool incorporating a core catcher of extremely large capacity as related to the size of the drilling bit of said tool whereby said tool is enabled to function as a fishing tool or junk catcher of extremely large capacity.

Another object of my invention is to provide a well drilling tool incorporating a core catcher and adapted for use as a fishing tool for catching both small and relatively large items or junk lost in the well.

Another object of my invention is to provide a tool of the character indicated which has a core catcher of such relatively large size as to enable the tool to take a core which could only be taken previously by an oversize head spring type catcher, and yet enable the tool to fish and hold small items previously handled by a regular head with dog type catchers.

A further object of my invention, therefore, is to obviate the need for different types and sizes of tools for coring or for fishing and to provide one tool capable of performing the work of said different types and sizes of tools with resultant economy and saving of time.

A further object of my invention is to provide a core catcher in which the structural details and their arrangement are of novel design and form enabling the provision of an extremely large core catcher in a core bit of regular size and in which the parts are sturdy, strong and wear-resistant to a high degree.

The various objects and features of my invention will be fully understood from the following detailed description of a typical preferred form and application of the invention, throughout which description reference is made to the accompanying drawings, in which:

Fig. 1 is a longitudinal broken elevational view in quarter section of a core drill embodying my invention.

Fig. 2 is a cross sectional view taken as indicated by the line 2—2 of Fig. 1.

2

Fig. 3 is an enlarged fragmentary cross sectional view taken as indicated by the line 3—3 of Fig. 1.

Figs. 4 and 5 are fragmentary vertical sectional views taken as indicated by the lines 4—4 and 5—5 of Fig. 3, respectively.

The core catcher of my invention is adapted to be embodied in or applied to core drill or coring devices of various types. In the following detailed specification I will disclose a typical preferred form of the invention embodied in a typical core drill, it being understood that the invention is not intended to be limited or restricted to the specific form or application described, but is to be considered as including such features or modifications which may fall within the scope of the invention as claimed.

The drawing illustrates a single barrel core drill involving the invention and which may be said to comprise, generally, a barrel 10, a bit head 11 carried by the barrel 10 and respective upper and lower core catcher units 12 and 13 carried by the bit head 11 and each having retractable fingers or dogs.

The barrel 10 is adapted to be attached to the lower end of an operating string of drill pipe or the like, and to receive the core cut by the bit head 11. The barrel 10 is a generally tubular member which may be of any desired length. In accordance with the usual practice, the barrel 10 may be provided at its upper end with a threaded box 14 for receiving a mating pin on the lower end of a string of drill pipe. Said upper end 15 of the barrel 10 is shown as smaller in diameter than the remaining elongated portion 16 of the barrel. A central longitudinal opening 17 is provided in said portion 16 for receiving the core cut by the drill, said opening 17 having connection with the box 14 by means of a smaller aligned opening 18. The lower end of the barrel portion is somewhat reduced in diameter to provide an annular shoulder 19 and said reduced end is externally threaded as at 20.

The bit head 11 is operable to make an annular cut in the earth formation to form a core to be received by the barrel 10. Said bit head 11 comprises a tubular member 21 having internal threads 22 for connection with the threaded end 20 of the barrel 10 and engaged with the shoulder 19 thereof to form a rigid extension of said barrel. The lower end of the bit head 11 is provided with an inreaching annular flange 23 defining a central cylindrical opening 24 which, in the present case, approximates the opening 17 in size and is longitudinally aligned therewith. The bit head 11,

between the flange 23 and the bottom end of the barrel 10, has an opening 25, larger in diameter than either opening 17 or 24, providing a connecting chamber for said openings 17 and 24 in which the core catcher units 12 and 13 are located. The bit head 11 is provided with earth formation cutting parts 26. Generally, and in a conventional manner, the cutting parts 26 comprise integrally connected cutting blades on the tubular member 21 which project outwardly and downwardly from the lower end of said tubular member. The cutting blades 26 are spaced apart circumferentially and disposed to make an annular cut in the earth formation and to form a core which is adapted to pass into the chamber 25 and into the opening 17 with suitable clearance.

Generally, the above-described core drill comprising the barrel 10 and the bit head 11, is of conventional form. However, the proportion and arrangement of the parts have been designed with the view of providing a core drill particularly suitable for the present invention. It will be noted that the barrel 10 comprises a single element of strong and easily manufactured design, whereas, heretofore, the barrel was made of several parts such as barrel tubes, subs, adapters, etc. By means of the construction which I have provided, the openings 17 and 24 and the chamber 25 can be and are extremely large, diametrically, with relation to the size of the tool as a whole. By means of my construction, the tubular member 21 can have a relatively thin yet strong tubular outer wall whereby the maximum practical diameter of the chamber 25 is afforded. Accordingly, I am enabled to make the core receiving openings 24 and 17, commensurately large. When the above-described tool is lowered into a well bore, the cutters 26 penetrate the formation leaving a core which is received in the aligned openings 24 and 17 and chamber 25.

The tool which I have provided, in addition to functioning as a core catcher, can be advantageously used as a finishing tool or junk catcher. Accordingly, I provide the upper core catcher unit 12 for the primary purpose of breaking out the core which is formed by the tool and the lower core catcher unit 13 for the primary purpose of engaging items which may be lost in the well and which may vary greatly in size. Generally, I provide each unit 12 and 13 with a plurality of in-reaching radially disposed retractable fingers or dogs, the dogs 30 and 31 of the upper unit 12 being generally shorter than the dogs 32 and 33 of the lower unit 13. The dogs of the upper unit 12, when unretracted, extend toward the center of the chamber 25 but fall short thereof to leave a relatively large central opening 34 between their inner ends. Both sets of dogs are upwardly retracted by the core as it enters the chamber 25. The units 12 and 13 are essentially the same with the exception of the lengths of their respective dogs and with the further exception that the unit 13 is higher or wider than the unit 12. Accordingly, the following description of the unit 13 will serve to describe the unit 12 also.

The unit 13 comprises an outer ring 35 having a cylindrical inner wall 41a and having an in-reaching annular shoulder flange 36 at its lower end and a plurality of uniformly spaced slotted openings 37 extending upwardly from said lower end. In this case the unit 13 carries five each of the dogs 32 and 33 and, therefore, has ten openings 37. Between two of the openings, the ring

35 is slit through from top to bottom as at 38. Within the ring 35, and resting upon the shoulder flange 36, there is provided an inner ring 39 of lesser height than the ring 35 and having an annular recess 40 at its lower end into which said shoulder flange engages. The central opening or bore 41 of the inner ring 39 approximates the passage 24 in size so that said opening forms a continuation of said passage. The inner ring 39 is formed with a plurality of slotted openings or notches 42 in register with the slotted openings or notches 37 in the outer ring. The openings 42, however, extend downwardly from the top edge of the ring 39 and are, in part, co-extensive with the openings 37 to provide seats 43 for the dogs 32 and 33. Said seats 43 are each defined by the aligned or registered lateral walls of the registered notch-like openings 37 and 42, by an upper slightly angled wall 44 of the opening 37, and by a lower also angled wall 45 of the opening 42. The ring 39 is further provided with a peripheral groove or channel 46 which extends between the dog seats 43. The rings 35 and 39 are secured together by rivets or the like, 47 which I show arranged in two sets connecting the unslotted portions of the rings.

The dogs 32 and 33 are mounted in the seats 43 to extend radially inward. Each dog comprises an elongated member which is generally 30 wedge-shaped from its relatively thin end 48 to its thicker portion 49 adjacent a hole 50 in said dog for a pivot pin 51 engaged in the channel 46. Around the hole 50, the dog is formed with a radius 52 extending tangentially from the under surface 53 of the dog to a lug 54 directed at an angle to the elongated portion of said dog. In the unretracted position of the dog, the portion of its surface 53 adjacent to the radius 52 engages the angled wall 45 and the lug 54 engages the opposed angled wall 44 to provide two points of support for the dog on opposite sides of its pivot pin 51. Each pivot pin 51 extends laterally of the dog which it mounts and into the channel 46. Accordingly, said extending ends of each pin 45 are beveled as at 55 to conform with the circumferential curvature of the ring 35. By means of this structure the pins 51 are also prevented from being dislodged laterally.

It is apparent from the foregoing that as the tool forms a core, said core will progressively project into the chamber 25 and will retract the dogs 32 and 33 upwardly around their pivot pins 51. From Fig. 4 it will be seen that I have designed the core catcher so that the dogs can be fully moved out of the path of the core to be entirely clear of said core. I have, therefore, arranged the upper surface 56 of each dog to intercept a radius 57 equal to the radius 52 around the dog hole 50 so that said dog surface 56 is enabled to lie flat against the inner surface of the ring 35. In this fully retracted position the dogs are clear of the core.

The dogs 32 and 33 are retractable against spring or similar means which seek to swing the dogs down to their inreaching position as determined by the angled walls 44 and 45. For this purpose, each dog is provided with a slot 58 between and parallel to the sides of the dog to bifurcate its pivot end. Within the slot 58 and around the pivot pin 51, I provide a coiled or twist spring 59 having one end 60 bearing on the ring 35 and the other end 61 bearing on the dog.

From the above structure it will be seen that side thrusts on the dogs are taken by the side walls of the openings 42 of the inner ring 39 and

that longitudinal loading forces, which act downwardly only, are taken by the assembled rings 35 and 39 at their angled walls 44 and 45, the pins 51 serving merely to hold the dogs in position. It will be further seen that because of the engagement of the flange 36 and the shoulder 40, the rings 35 and 39 cannot separate axially in one direction, and because of the engagement of the dog lug 54 with the angled wall 44, said rings cannot separate axially in the other direction.

The tool above-described, after forming a core which projects upward into the barrel passage 17, can be operated to break out said core. This core breaking operation is performed by raising the tool so that the bit head 11 is lifted from the formation at the bottom of the well bore. Since the springs 59 urge the retracted dogs inwardly, said dogs are forced progressively further into the core as the tool is rotated and the core can be readily broken loose from the formation by pulling upwardly on the tool. It is evident that the shortest dogs 30 will more efficiently bite into the core because the change in the angular position is more rapid as said dogs are forced into the core. The other longer dogs 31, 32 and 33, while less efficient as core cutters because of their greater length, function more efficiently as catchers for items lost in the well bore. I have, therefore, provided each dog with side bevels 62 for the purpose of providing cutting edges adapted to cut in the core and, in the case of the longest dogs 33, for the further purpose of obtaining the maximum length of said dogs 33 as best seen in Fig. 2.

Each of the units 12 and 13 are easily assembled. The dogs are first mounted on the ring 39, the split outer ring 35 is then sprung over the dogs, pulled into place, and riveted together as described. The catcher units thus provided afford maximum support for the dogs with minimum thickness of the rings 35 and 39 resulting in the ability of the tool to handle an extremely large core. Also, the flange 23 of the bit head fully supports the catcher unit 13, and the latter in turn, fully supports the unit 12 when the tool is pulled upwardly to break the core. Further, the flange 36 of each unit takes the upward thrust of the tool as imparted to the ring 35 of each unit, to remove the shear on the rivets 47.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. Core breaking and catching means including, a vertical external elongate ring having an inwardly directed annular shoulder flange at its lower end, a vertical internal ring of lesser height than the external ring arranged within the external ring and engaged with said shoulder flange, means connecting said rings, a plurality of seats comprising aligned notches formed in both rings, a plurality of like dogs, means pivotally mounting a dog in each seat, and resilient means engaging each dog and normally yieldingly holding it in position where it extends substantially radially of the rings and is inwardly directed from its point of pivotal mounting.

2. Core breaking and catching means including, a vertical external split ring having an inwardly directed annular shoulder flange at its lower end, an internal ring of lesser height than the external ring arranged within the external

ring and engaged with said shoulder flange, means connecting said rings, there being aligned notches formed in both rings establishing a plurality of circumferentially spaced seats, a plurality of like dogs, means pivotally mounting a dog in each seat, and resilient means engaging each dog and normally yieldingly holding the dog in a position where it extends substantially radially of the rings and inwardly from its point of pivotal mounting.

3. In a core breaking and catching means, a vertical external ring having an internal cylindrical wall and a lower inwardly directed annular shoulder flange, an internal ring of lesser height and greater thickness than the external ring and located within the cylindrical wall of the external ring and engaged with said shoulder flange, the said external and internal rings having registering dog receiving notches, there being a pin carrying channel in the exterior of the internal ring, and means joining the rings together with said wall of the external ring closing said channel.

4. A core breaking and catching unit including, a vertical outer thin walled split elongate cylindrical ring having an inwardly directed annular shoulder flange at its lower end portion and a plurality of downwardly opening notches in its lower end portion, an inner ring arranged within the first mentioned ring and seated on said shoulder flange and having a wall thicker than that of the outer ring with a plurality of upwardly opening notches aligned with the first mentioned notches and in communication with the first mentioned notches to form a plurality of seats, the upper end of the inner ring terminating below the upper end of the outer ring, a plurality of tapered dogs, pivot pins held between the rings and pivotally mounting a dog in each seat, resilient means engaging each dog and normally yieldingly holding it in a position where it extends radially of the rings and inward toward the center of the unit, each dog being adapted to be retracted to assume a position with its upper side substantially parallel with the first mentioned ring while its lower side extends upwardly and outwardly, and means joining the rings together holding the dogs and pins.

5. A core breaking and catching unit including, an outer thin walled split elongate cylindrical ring having an inwardly directed annular shoulder flange at its lower end and a plurality of downwardly opening notches in its lower end, an inner ring seated on said shoulder flange and having a wall substantially thicker than that of the outer ring and having a plurality of upwardly opening notches in its wall aligned with the notches of the outer ring to form a plurality of seats, said inner ring being formed with an annular outwardly faced circumferential groove interconnecting said seats and closed by the inner side of the wall of the outer ring, pivot pins in said groove retained therein by the inner ring and each extending across a seat, and a dog pivotally carried on each pivot pin and normally radially directed toward the center of the unit.

6. A core breaking and catching unit including an outer thin walled split elongate cylindrical ring having an inwardly projecting annular shoulder flange at its lower end and a plurality of downwardly opening notches in its lower end, an inner ring engaged in the outer ring and on said shoulder flange and having a plurality of upwardly opening notches aligned with the notches of the outer ring to form a plurality of

seats, said inner ring being substantially thicker than the outer ring and terminating a substantial distance below the upper end of the outer ring and being formed in its outer wall with an annular outwardly faced circumferential groove interconnecting said seats, pivot pins in said groove and each extending across a seat and retained in place by the inner cylindrical wall of the outer ring, and a retractable tapered dog pivotally carried on each pin, each dog being normally radially directed inward toward the center of the unit and adapted to be retracted to assume a position where it extends upwardly so its outer side bears on and is substantially parallel to the inner wall of the outer ring while its inner side extends upwardly and outwardly. 15
